(No Model.)

T. C. SEAMAN.

MACHINE FOR CROZING, CHAMFERING, AND HOWELING BARRELS.

No. 284,245.

Patented Sept. 4, 1883.

UNITED STATES PATENT OFFICE.

THOMAS C. SEAMAN, OF CHICAGO, ILLINOIS.

MACHINE FOR CROZING, CHAMFERING, AND HOWELING BARRELS.

SPECIFICATION forming part of Letters Patent No. 284,245, dated September 4, 1883.

Application filed July 19, 1882. (No model.)

To all whom it may concern:

Be it known that I, THOMAS C. SEAMAN, of Chicago, county of Cook, and State of Illinois, have invented certain new and useful Improvements in Machines for Working-Off Kegs and Barrels, of which the following is a full, clear, and exact description, that will enable others skilled in the art to which it appertains to construct and operate the same, reference being had to the accompanying drawings, and to letters of reference marked thereon, forming a part of this specification.

This invention relates to that class of barrel-machines that are employed in trimming off the ends of the barrel or package, chamfering the chine, and howeling and crozing, so that the barrel is all completed and ready to receive the heads and hoops.

Figure 1 is a side elevation of a machine, partially in section, embodying my improvements. Fig. 2 is a transverse section in the plane $x x$, Fig. 1, giving an inside face view of the cutting mechanism.

Referring to the drawings, A A' represent the two side pieces, and A² A³ the legs, forming the supporting-frame work. The head-blocks B B' are adapted to have a longitudinal adjustment and movement on the side pieces, A A', for the purpose of bringing these parts nearer to each other, so as to clamp and hold barrels or kegs of different lengths. In practical operation, however, the block B is set at the desired point and secured in a stationary position by means of the screw-bolt B² and the clamping-plate B³. The head-block B' is retained in position by means of the bolt A⁴ and the plate B⁴, but is not rigidly secured, and is moved by the operator pressing on the treadle-board C, as shown by the dotted lines in Fig. 1. This adjustment is accomplished through the medium of the cord C', passing over the guide-pulley C², which connects the treadle-board and the clamping-disk C³, which forms a rigid part of the head-block B'. When the pressure is relaxed on the treadle-board, the head-block B' is automatically returned to a normal position by means of the spiral spring C⁴. The head-block B is provided with a clamping-disk, D, corresponding to the disk C³. These clamping-disks are constructed with a large opening for the reception of the detachable rings, which are secured in rela-

tion thereto by the screws a². (Shown in Fig. 2 of the drawings.) The detachable rings a a' are slightly conical and fit into a corresponding bearing in the clamping-disks.

This machine is adapted to work-off both ends of a package at the same time. The description, therefore, of one end will refer as well to the opposite end, as both are substantially alike in construction and operation.

The band-pulley a³ is mounted on the hollow shaft D', which is provided with the journal-bearings a⁴ a⁵. This hollow shaft has a rotary but not a longitudinal movement. On the inside of this hollow shaft is placed the shaft D², which has both a rotary and a longitudinal movement, rotating with but not independent of the inclosing tubular shaft. The shaft D² is provided near the outer end with the longitudinal groove b, into which fits the screw or pin b', which serves to secure the two shafts relatively to each other, so as to compel both shafts to rotate at the same time, and also to provide for a longitudinal or endwise adjustment of the inner shaft. The outer end of the shaft D² has a journal bearing or box, b², which is placed in the enlarged part b³ of the operating-lever D³. The lever D³ is provided near its longitudinal center with the enlarged rectangular part b⁴, which is provided with an opening for the reception of the journal-box b², supporting the end of the inner shaft, D². The journal-box b² is provided on each side with the lateral projecting pin b⁴, which engages with the slots d in the enlarged part b³, and serves to retain these parts in proper relation with reference to each other, so that as the lever D is moved in or out a corresponding movement is imparted to the shaft D². By means of the elongated slot d in the edges of the part b³, the lever D³ is permitted to have a slight vertical adjustment in order to conform to the change of position when the same is moved away from or toward the machine proper.

On the inner end of the tubular shaft D' is rigidly secured the annular cutter-plate E, carrying on the inner face thereof the different cutters required. The block d' on the cutter-plate is adapted to have a lateral adjustment, and is provided with the elongated slot d', through which projects the inner square end of the shaft D². The two alternate cor-

ners of the block d' are cut away on a bevel, as shown in Fig. 2 of the drawings, for the engagement of the inner pivoted ends of the arms $d^3 d^4$. The outer ends of these arms are secured to the cutter-plate by means of the screws $f' f'$, allowing the inner pivoted ends to move freely with the block d' .

To the upper and lower sides of the block d' is attached, by means of the screws $b^5 b^6$, the angular tool-holding stocks $F F'$. The part of the tool-holder having a bearing on the block d' is provided with a rectangular slot on the upper and lower edge, so that the cutting mechanism may be adjusted to a greater or less diameter, as may be required in working off packages of different sizes. The outer ends of the tool-holding stocks are recessed for the reception of the cutters, which are secured in position by means of the set-screws $d^3 d^4$. The cutter F^2 does the leveling and the companion cutter, F^3 , the howeling, while the cutter F^4 on the opposite side does the crozing, and the companion hook-shaped cutter, F^5 , clears out the croze, which completes the package ready

for the permanent hoops and heads. To the inner square end of the shaft D^2 is attached one end of the cord H , which passes up under the guard-sheave h , and is secured at the other end to one end of the block d' by means of the screw h' . One end of a companion cord, H' , is secured to the shaft D^2 at h^2 , the opposite end passing over the guide-sheave h^3 , and being attached to the opposite end of the block d' by the screw h^4 . Now, by this arrangement, when the operating-lever is shifted in one direction, one set of cutters is thrown outward toward the edge of the cutter-plate and brought in working position, while the cutters on the opposite side are drawn away

from the work, and by moving the operating-

lever in the opposite direction the position of the expansible cutters is reversed, the longitudinal movement of the shaft D^2 being simultaneous with that of the operating-lever.

The ring a' is placed in the clamping-disk C^3 , and is a duplicate of the ring a . (Shown in section in the companion clamping-disk, D .) Any required number of sets of the rings $a' a'$ may be used, each set being of a different diameter, in accordance with the diameter of the package to be worked off. Both ends of this machine are alike, the different parts being exact duplicates of the other and adapted to work off both ends of the package at the same time, the barrel or keg being held in a stationary position while the crozing mechanism revolves.

Having thus described my invention, what I claim as new, and desire to secure by Letters Patent, is—

The combination, with the inner end of the shaft D^2 , adapted to have both a rotary and a longitudinal movement, of the cutter or face plate E , the lateral moving block d , provided with the elongated aperture d^2 , the arms $d^3 d^4$, having one end pivoted to the face-plate E and the opposite end attached to and moving with the block d , the tool-holding stocks $F F'$, attached to and having a lateral adjustment on the block d , the cords $H H'$, and the guide-sheaves h^3 , whereby the cutting mechanism is brought into contact with or moved away from the work by an endwise movement of the shaft D^2 , substantially as and for the purpose described.

THOMAS C. SEAMAN.
